US00D900121S

(12) **United States Design Patent** (10) Patent No.: **US D900,121 S**
(45) Date of Patent: **** Oct. 27, 2020**

(54) **POSITIONABLE GRIPPING DEVICE**

(71) Applicant: **Grip Curl, LLC**, Chandler, AZ (US)

(72) Inventors: **Derrick Pierson**, Chandler, AZ (US);
Charles Pierson, Chandler, AZ (US);
Aaron Bickel, Chandler, AZ (US)

(73) Assignee: **Grip Curl, LLC**, Chandler, AZ (US)

(**) Term: **15 Years**

(21) Appl. No.: **29/717,351**

(22) Filed: **Dec. 17, 2019**

CLAIM

The ornamental design for a positional gripping device, as shown and described.

DESCRIPTION

FIG. 1 is a front view of a positionable gripping device showing the claimed design;

FIG. 2 is a back view of the positionable gripping device shown in FIG. 1;

FIG. 3 is a perspective view of the positionable gripping device shown in FIG. 1 with a gripping element in a first position;

FIG. 4 is a perspective view of the positionable gripping device shown in FIG. 1 with a gripping element in a second position;

FIG. 5 is a side view of the positionable gripping device shown in FIG. 1 with a gripping element in the first position; and,

FIG. 6 is a side view of the positionable gripping device shown in FIG. 1 with a gripping element in the second position.

The broken lines in the figures form no part of the claimed design.

1 Claim, 2 Drawing Sheets
